US0D1016076S

(12) **United States Design Patent** (10) **Patent No.:** **US D1,016,076 S**
(45) **Date of Patent:** **** Feb. 27, 2024**

(54) **DEVICE MOUNT**

- (71) Applicant: **Amazon Technologies, Inc.**, Seattle, WA (US)
- (72) Inventors: **Jesse Moore**, Oakland, CA (US); **Emmanuel Laffon de Mazieres**, Burlingame, CA (US)
- (73) Assignee: **Amazon Technologies, Inc.**, Seattle, WA (US)

(**) Term: **15 Years**

(21) Appl. No.: **29/813,262**

(22) Filed: **Oct. 27, 2021**

CLAIM

The ornamental design for a device mount, as shown and described.

DESCRIPTION

FIG. 1 is a top perspective view of a device mount;

FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the device mount that form no part of the claimed design.
